T. J. DAVIS

GOLF CLUB

Filed Dec. 29, 1923

INVENTOR
Thomas J. Davis
BY
John H. Marr
ATTORNEY

UNITED STATES PATENT OFFICE.

THOMAS JAMES DAVIS, OF BROOKLYN, NEW YORK.

GOLF CLUB.

Application filed December 29, 1923. Serial No. 683,412.

To all whom it may concern:

Be it known that I, THOMAS J. DAVIS, a citizen of the United States, and resident of the borough of Brooklyn, county of Kings, 5 city and State of New York, have invented certain new and useful Improvements in Golf Clubs, of which the following is the specification.

The object of the invention herein set 10 forth is to construct a golf club, providing it with means for encouraging the user and particularly the amateur or student to "carry through", the attack upon the ball.

It is well known that the so termed "carry 15 through" is exceedingly important and yet difficult of attainment. The amateur or student starts the club from the shoulder with certain vim and velocity, but as the club approaches the ball, the head of the 20 club is slowed down until the contact is at a force less than that desired. The swing is neither complete nor artistic and this so called "choking" of the stroke is noticeable even in players of long experience, the 25 "choking" resulting most often from nervousness or overanxiety.

To encourage a "carry through" is then the object of this invention and the following is what I consider the best means of carrying out this invention and the accompanying drawing should be referred to for a complete understanding of the specification 30 which follows:—

In the drawing:—

Fig. 1, is a sectional, plan view of a golf 35 club, commonly termed a driver.

Fig. 2, is a vertical, sectional view.

Fig. 3, is a perspective view of the driver.

Fig. 4, a sectional, plan view of a modification.

Similar reference numerals indicate like parts in all the figures where they appear.

The handle or staff of my club is of ordinary length, shape and contour and I therefore show but a small fraction of the staff as indicated at 1.

The club head should be made of wood and may or may not be metal faced. The shape of the head and the facing are not in my invention changed from the ordinary and well known standards. The head is provided with a stem as shown at 2, to which the staff of handle is secured, by any suitable means, such as the mousing cord 3.

Within the head and quite local to the impact face 4 of the club, I produce a well 5

and connected with the well is a channel 6, which extends the length of the club head, continuing upward into the stem 2, as shown at 7. The well and channel must be water 60 tight and I therefore place a plate 8 over the well as shown in Figs. 2 and 3. The channels or canals in the head may be formed by boring and if bored in the general manner shown, plugs 9 and 10 are introduced to close the continuations of the canal, which it was necessary to produce to give the canal the proper angle and a plug or dowel 11, secured to or formed integral with the shaft or staff 1 enters that part 7 70 of the canal which is produced in the stem 2.

Before describing the function of the well and connecting canals, I will describe the construction as shown in Fig. 4.

Here the club is divided at approximately 75 mid-height and with a routing tool the canal 12 and well 13 are produced. The boring tool may produce the canal 12 in the stem 2. One-half of the canal 12 and well 13 may be produced in each the bottom and top halves 80 of the head and when the two parts of the head are secured together, a cylindrically shaped canal and suitably shaped well are produced. The two parts of the club head may be secured by means of screws 15, but 85 should be also cemented together, so that the canal and well will be water tight.

As shown by the dotted line 16, the channel may be continued into and even through the shaft or handle, thus providing greater 90 travel for the mercury.

The length of travel will be determined by the speed of travel of the mercury, it being the desire that the mercury reach the face of the club at the time that the face reaches 95 the ball.

Into the canal and well, I place metallic mercury, the quantity used being that quantity which will be contained almost fully within the well. The mercury can readily 100 pass through the channels or canals and when the club is lifted, the mercury will be wholly within the stem 2. The downward movement of the club, in making a stroke will cause the mercury to rush into 105 the well, encouraging the user of the club to continue the swing to its full extent.

Other modifications may be made within the scope of the appended claims without departing from the principle or sacrificing the 110 advantages of the invention.

Having carefully and fully described my

invention, what I claim and desire to obtain is:—

1. A head for golf clubs provided with a channel, a portion of which extends parallel with the face and a portion of which is at right angles to the face and a movable member in said channel, adapted to approach the face of the head, during the stroke, said movable member comprising metallic mercury.
2. A golf club having a head and a handle, both of which are provided with a channel, a portion of which extends parallel with the face of the club and a portion of which is at right angles to the face and a movable member in said channel, adapted to approach the

face of the head, during the stroke, said movable member comprising a metal in semi-liquid form.

3. A head for golf clubs provided with a channel, a portion of which extends parallel with the face and a portion of which is at right angles to the face and a movable member in said channel, adapted to approach the face of the head, during the stroke, said channel being of cylindrical form and having a well of greater diameter adjacent the face.

Signed at the city, county and State of New York, this 12th day of November, 1923.

THOMAS JAMES DAVIS.
